DEVICE FOR SHARPENING SCISSORS AND
LIKE CUTTING IMPLEMENTS

William T. Martin, Tampa, Fla.

Application November 3, 1937, Serial No. 172,603

3 Claims. (Cl. 51—214)

This invention relates to improvements in devices for sharpening scissors and like cutting implements having blades which require a straight cutting edge.

5 Among the objects of the invention may be noted the provision of a device for sharpening scissors and the like cutting implements having a blade or blades requiring a straight cutting edge, which is simple and inexpensive in manufacture, rugged and durable in use, and which is highly efficient in operation; the provision of a device of the above character which is so designed as to preserve the straight cutting edge of the blade or like part of the implement being 10 sharpened; the provision of a sharpener which will accommodate cutting blades of varying thicknesses; and the provision of a sharpening device incorporating a sharpening element and a holder therefor, in which the element may readily be 15 inserted into and removed from the holder, thus to provide for replacement or interchangeability of the sharpening element with respect to its holder.

Other objects will be in part obvious and in 20 part hereinafter pointed out in connection with the following analysis of this invention wherein is illustrated an embodiment of the invention in detail.

In the drawing—

30 Fig. 1 is a perspective view of a sharpening device in accordance with the present invention;

Fig. 2 is a longitudinal section through the device illustrated in Fig. 1; and

Fig. 3 is illustrative of a blank from which the 35 holder for the sharpening element is fabricated.

Referring now to the drawing wherein like reference characters designate like parts throughout the several views, the sharpening device of the present invention is provided by a sharpening element and a holder therefor, of which the holder, generally designated 10, is fabricated from a sheet metal blank as shown in Fig. 3 to provide an open top box-like structure having a bottom 11, upstanding front and rear walls 12, 13, respectively, and end walls 14 and 15.

The holder 10 is adapted to receive a sharpening element 20 which may be constituted by abrasive material cast or otherwise formed into a block for insertion into the holder, or introduced into the holder in plastic form, there to dry and harden. Or the sharpening element may be constituted by a metal member having its upper surface formed to provide a sharpening surface. The dimensions of the sharpening element are substantially the dimensions of the

holder bottom 11, and element 20 is arranged to lie against the bottom 11 of the holder. By reason of the springy nature of the sheet metal from which the holder is constituted, the ends 14, 15 may flex relatively outwardly as the block-like 5 sharpening element is positioned in the holder, and the ends are provided with element securing means, in the nature of a series of indentations 21 spaced from the bottom of the holder slightly in excess of the depth of the sharpening element. 10 The arrangement is such that the sharpening element may be pressed home against the bottom 11 of the holder, with the ends thereupon springing back to initial position and indentations 21 15 therein acting to secure the block 20 within the holder. Where the abrasive material is introduced in plastic form, the indentations 21 serve in similar manner to secure the hardened material in the holder.

Each of the front and rear walls 12, 13 of the 20 holder are provided with a plurality of blade receiving slots, the slots of the front wall 12 being designated 25a, 25b, 25c, and the slots in the rear wall 13 being designated 26a, 26b, and 26c. While three sets of blade receiving slots are 25 shown, it will be understood that this is for purpose of illustration only.

The arrangement is such that slots 25a, 26a of the walls 12, 13 are similarly dimensioned and are arranged in alignment. In like manner slots 30 25b and 26b are similarly dimensioned and aligned, as are slots 25c, 26c.

In order that the sharpener shall accommodate implement blades of varying thicknesses, the width of the slots is stepped; that is to say, the 35 aligned slots 25a, 26a are wider than slots 25b, 26b, and these latter slots are wider than the slots 25c, 26c. Thus the blade of the scissors or like implement to be sharpened may be inserted in whichever set of aligned slots will comfortably receive it.

In order to accommodate for the bevel cross section of a blade, such as scissors blade, one side of the several slots is inclined or flared outwardly with respect to the other side thereof. Thus, by 45 reference to the drawing, it will be seen that the right edge of the several slots is substantially inclined to the left edge, whereby a blade entering the slot through its open top, with the blade edge in down position, may be suitably received in the 50 slot despite its irregular cross section.

It will be further noted from the drawing that the leftwise edges of all of the slots are parallel and, while shown in right angular relation to the sharpening surface of element 20, they may be 55

slightly inclined with reference thereto, thus to present the beveled cutting edge to the sharpening surface. It is intended that the inside or straight-face of the blade being sharpened shall 5 be held against the leftwise edges of the aligned slots which receive it and, to indicate that this placement should obtain under all conditions, the end wall 14 of the holder may carry suitable indicia such as the word "Front" stamped therein 10 to indicate to the user the proper placement of the blade in the sharpener.

By reference to the drawing it will further be seen that the depth of the several slots is such that the base portions thereof extend below the 15 upper or sharpening surface of the sharpening element 20. By this arrangement long life of the device is assured even though there has occurred substantial wear of the sharpening element such as to cause the formation of grooves thereacross.

20 In use of the device as described, the blade of the scissors or like implement whose cutting edges are to be sharpened is inserted in whichever pair of aligned slots that will receive it, with the blade so disposed that its cutting edge will 25 contact the sharpening surface of the element 20, with the inner or straight face of the blade disposed against the leftwise edge of the receiving slots. The blade is thereupon pressed down on the sharpening surface of the element and 30 either the blade stroked back and forth across the element, or the sharpening device is stroked back and forth across the blade. As the sharpening element has substantial width, the straight edge of the blade is suitably supported thereon and the straightness of the edge preserved during 35 the sharpening action.

As many changes could be made in carrying out the above construction without departing from the scope of the invention, it is intended that all matter contained in the above description or shown in the accompanying drawing shall 40 be interpreted as illustrative and not in a limiting sense.

I claim:

45 1. A scissors sharpener comprising a sharpening element and a holder therefor, the holder being of sheet metal construction and having a substantially rectangular bottom wall and up-

standing front, rear and end walls extending therefrom, the sharpening element being rectangular in shape and substantially coextensive with said bottom wall and being supported thereon to provide an upper sharpening face extending 5 between said front, rear and end walls, at least the front and rear walls being of substantially greater height than that of said sharpening element, and said front and rear walls being provided with sets of aligned and upwardly opening 10 blade-receiving slots.

2. A scissors sharpener comprising a sharpening element and a holder therefor, the holder being of sheet metal construction and having a substantially rectangular bottom wall and up- 15 standing front, rear and end walls extending therefrom, the sharpening element being rectangular in shape and substantially coextensive with said bottom wall and being supported thereon to provide an upper sharpening face extending 20 between said front, rear and end walls, the end walls having provisions for securing the sharpening element against the bottom wall, at least the front and rear walls being of substantially greater height than that of the sharpening ele- 25 ment, and the front and rear walls being provided with sets of aligned and upwardly opening blade-receiving slots.

3. A scissors sharpener comprising a sharpening element and a holder therefor, the holder 30 being of sheet metal construction and having a substantially rectangular bottom wall and up- standing front, rear and end walls extending therefrom, the sharpening element being rectangular in shape and substantially coextensive 35 with said bottom wall and being supported thereon to provide an upper sharpening face extending between said front, rear and end walls, the end walls having provisions for securing the sharpening element against the bottom wall, at least 40 the front and rear walls being of substantially greater height than that of the sharpening element, and the front and rear walls being provided with sets of aligned and upwardly opening blade-receiving slots, said slots extending down- 45 wardly to a level substantially below that of the upper face of the sharpening element.

WILLIAM T. MARTIN.
